HELMET CAP

Philip Davis, Brooklyn, N. Y.

Application January 22, 1934, Serial No. 707,758

4 Claims. (Cl. 2-205)

This invention relates to new and useful improvements in a helmet cap.

The invention has for an object the construction of a helmet cap which is characterized by a substantially dome-shaped piece of knitted material for engaging completely over one's head and formed with an opening on one side for exposing the face.

Still further the invention proposes arranging the knitted material with a tuft at the top.

Still further the invention also contemplates the provision of a flap or flaps upon the edge of said opening.

Still further the invention proposes an arrangement whereby a plurality of flaps are arranged along the edge of the opening and a means is provided to hold these flaps to the outside of the knitted material or the inside of the knitted material forming said helmet cap.

As another object of this invention an arrangement is proposed whereby the edges of the opening may be contracted for changing its size.

Still further the invention proposes the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a helmet cap constructed according to this invention.

Fig. 2 is a vertical sectional view taken on the line 2—2 of Fig. 1.

Fig. 3 is a view similar to Fig. 1 but illustrating a modified arrangement.

Fig. 4 is a fragmentary horizontal sectional view taken on the line 4—4 of Fig. 3.

Fig. 5 is a view similar to Fig. 1 but illustrating another embodiment of the invention.

Fig. 6 is another view similar to Fig. 1 but illustrating another embodiment of the invention.

Fig. 7 is a fragmentary sectional view taken on the line 7—7 of Fig. 6.

Fig. 8 is a similar view to Fig. 7 illustrating another modified arrangement of the invention.

The helmet cap illustrated in Figs. 1 and 2 comprises knitted material 10 of substantially dome-shape for engaging completely over one's head and formed with an opening 11 upon one side for exposing the face. The knitted mate-

rial 10 preferably should be formed by knitting on a conventional circular knitting machine and producing tubular knitted material which is thereafter cut into small tubular pieces. A cord 12 may then be used for drawing one end of each of the tubular pieces together to produce a tuft 13 and at the same time to form the dome-shape previously described. Each piece is used to form a cap. The cap has its lower edge 14 rolled so as to smartly finish the lower edge of the cap. The edge of the opening 11 is formed with stitches 15 serving to finish it to prevent unraveling of the knitted material and also to add to the ornamental effect.

A flap 16 is knitted integral with the material 10 and extends from one edge of the opening 11. This flap is turned upwards as clearly illustrated in Figs. 1 and 2 and secured in a raised position by several stitches 17. These stitches 17 also secure buttons 18 upon the flap for ornamental purposes. The opening 11 preferably should be of heart shape and is so illustrated merely for ornamental purposes.

In Fig. 3 a modified form of the article has been disclosed which is substantially similar to the construction illustrated in Figs. 1 and 2, similar parts may be recognized by the same reference numerals, but departing merely in the arrangement of flaps upon the edge of the opening 11. In the prior device just one flap was provided, arranged at the top of the opening so as to be located upon the forehead of a wearer of the cap. In the form illustrated in Fig. 3 a pair of flaps 16' are integral with the knitted material and arranged upon the opposite sides of the opening 11. These flaps 16' assume positions over the cheeks of a wearer of the helmet cap. Buttons 18 are secured down upon the flaps 16' by threads (similar to the threads 17 illustrated in Fig. 2) which also hold the flaps 16' in position.

In Fig. 5 another embodiment of the invention has been disclosed which is very similar to the form illustrated in Fig. 1 distinguishing, in the provision of a cape portion 20 at the bottom of the helmet cap for the purpose of slightly extending over the shoulders of a wearer. The lower edge of this cape portion is finished by stitches 21. Still further the helmet cap is provided with an opening 11' for exposing the face.

In Figs. 6 and 7 another variation of the invention has been disclosed in which several flaps 22 and 23, are arranged around the edges of the opening 11. These flaps are provided with hook elements 24 having points 25 extended in opposite

direction so as to be engageable against the knitted material 10 with the flaps on the outer or the inner sides. These hooks 24 serve to hold the flaps in either position stated. The flap 22 5 is shown secured upon the outer side while the flaps 23 upon the inner side. This arrangement provides flexibility whereby all of the flaps may be arranged upon the outer side or the inner side or various combinations.

10 A feature of arranging the flaps as stated lies in the fact that the design of the cap may thus be controlled by setting the cap to the features of a wearer. Some persons will undoubtedly look better with the flaps in one condition and other 15 persons with the flaps in other condition depending upon the features of the face. Furthermore a means is provided for contracting the edges of the opening 11 to change its size and shape. This means comprises a cord 26 which is arranged 20 slidably within the stitches 15 which finish the edges of the opening 11. This cord has free ends 27 knotted together and arranged behind one of the flaps, preferably the top flap 22. It is possible to untie the ends 27 and tie the cord for the purpose of contracting the opening 11.

In Fig. 8, snap fastener members 24' are substituted in place of the hook elements 24. In other respects this arrangement is the same as disclosed in Figs. 6 and 7.

30 While I have shown and described the preferred embodiments of my invention, it is to be understood that I do not limit myself to the precise constructions herein disclosed and the right is reserved to all changes and modifications coming 35 within the scope of the invention as defined in the appended claims.

Having thus described my invention, what I

claim as new and desire to secure by United States Letters Patent is:—

1. A helmet cap, comprising knitted material of substantially dome-shape for engaging completely over one's head and formed with an opening on one side for exposing the face, a plurality of flaps along the edge of said opening, and means for holding said flaps outside or inside of said knitted material. 5

2. A helmet cap, comprising knitted material 10 of substantially dome-shape for engaging completely over one's head and formed with an opening on one side for exposing the face, a plurality 15 of flaps along the edge of said opening, and means for holding said flaps outside or inside of said knitted material, comprising hooks upon the flaps engageable with the material of said knitted material.

3. A helmet cap, comprising knitted material of substantially dome-shape for engaging completely over one's head and formed with an opening on one side for exposing the face, a plurality 20 of flaps along the edge of said opening, and means for holding said flaps outside or inside of said knitted material, and means for contracting the 25 edges of said opening.

4. A helmet cap, comprising knitted material of substantially dome-shape for engaging completely over one's head and formed with an opening on one side for exposing the face, a plurality 30 of flaps along the edge of said opening, and means for holding said flaps outside or inside of said knitted material, and means for contracting the edges of said opening, comprising a cord slidably mounted upon the edge of the opening and having 35 ends adapted to be tied together.

PHILIP DAVIS.
